UNITED STATES PATENT OFFICE.

GEORGE B. SNOW, OF ONEIDA, NEW YORK.

DESIGN FOR A SCREEN.

SPECIFICATION forming part of **Design No. 27,407**, dated July 20, 1897.

Application filed June 8, 1897. Serial No. 639,921. Term of patent 3½ years.

To all whom it may concern:

Be it known that I, GEORGE B. SNOW, a citizen of the United States, residing at Oneida, in the county of Madison and State of New York, have invented a new and original Design for a Screen, of which the following is a specification.

This invention relates to a new and original design for a screen; and it has for its object to provide a design of this character that shall be both useful and ornamental.

The leading feature of the design resides in a screen having an upright rectangular frame provided with a series of horizontal plain rectangular panels arranged one above the other and extending from side to side of the frame, said frame being further provided above the plane of its upper cross-bar with a raised ornament consisting of an arched strip joined 15 with the upper corners of the frame and having compoundly-curved upper and lower edges.

In the drawings, Figure 1 is a perspective view of a fire-screen embodying the herein-described design. Fig. 2 is an elevation thereof.

Referring to the accompanying drawings, the numeral 1 designates the upright rectan-

gular frame of the screen, essentially comprising opposite parallel side bars 2 and the 30 end cross-bars 3, connecting said side bars 2. The frame 1 is provided at its lower corners with short pendent leg projections 4 and has the opposite side bars 2 thereof connected by a series of regularly-spaced parallel stile-strips 5, between which strips are fitted plain rectangular panels 6, arranged one above the other and extending from side to side of the frame. 35

The upright frame 1 of the screen is provided above the plane of its upper cross-bar 3 with an ornament 7, consisting of an arched strip, the extremities of which are joined with the upper corners of the frame, and said strip is provided with compoundly-curved or regularly-scalloped upper and lower edges 8. 40 45

What I claim is—

The design for a screen, herein shown and described.

In testimony that I claim the foregoing as 50 my own I have hereto affixed my signature in the presence of two witnesses.

GEORGE B. SNOW.
